FOLLOW REST FOR LATHES

Edward N. Lichtenberg, Claymont Heights, Del.,
assignor to Remington Arms Company, Inc.,
Bridgeport, Conn., a corporation of Delaware

Application April 14, 1949, Serial No. 87,404

6 Claims. (Cl. 51—238)

1

The present invention relates to an improved follow rest for machines for turning, grinding, or the like, and more particularly such machines used in the manufacture of gun and rifle barrels and similar work having a relatively long thin shaft of circular cross section. An object of the invention is to provide a follow rest adapted for mounting directly upon the carriage of the machine, and including means arranged to bear on the turned portion of the barrel or other work in proximity to the cutting, grinding or similar tool to provide evenly distributed support for the work, to the end that the tendency of the tool to throw the work off center is resisted and the concentricity of the work is maintained. It is particularly proposed, in the illustrated exemplary embodiment of the invention, to provide three rolls mounted on bell cranks and equally spaced around the periphery of the work a short distance behind the tool, these rolls being constrained to move in substantially radial arcs in exactly equal amounts, so that when the center of the three rolls is on the spindle center line of the machine the concentricity of the turned portion of the work is maintained, the resultant pressure of the rolls on the work counter-balancing the tool pressure. It is further proposed to provide fluid pressure means, as for instance an air cylinder, for providing the pressure for maintaining the rolls in engagement with the work, and whereby the rolls are automatically maintained in engagement with the work under controlled pressures as the rolls move radially to accommodate the changing diameter of the work as the turning, grinding or similar operation progresses.

A further object is to provide a follow rest having self-aligning rolls having a relatively large area of contact with the work and adapted to align themselves with the changing contour of the work throughout its length, to the end that a substantial total pressure may be applied to the rolls without excessive unit pressures, such as may be encountered when there is a small area or point contact of the rolls with the work. With the relatively high roll pressures that are necessary to support the barrel or other work against the tool pressure, this small area or point contact may result in unit pressures in excess of the elastic limit of the barrel steel with consequent objectionable reaction upon the barrel structure.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a front elevation of the follow rest, according to the illustrated exemplary embodiment of the invention, the same being shown par-

2

tially in vertical section, and the dot-and-dash lines indicating a lathe carriage to which the follow rest is attached.

Fig. 2 is a top plan view.

Fig. 3 is a vertical sectional view, taken along the staggered line 3—3 of Fig. 1.

Fig. 4 is a side elevation, as seen from the left in Fig. 1.

Fig. 5 is a fragmentary sectional view, on an enlarged scale, showing one of the pressure rolls and certain associated parts.

Similar reference characters indicate corresponding parts throughout the several figures of the drawings.

Referring to the drawings, the follow rest, according to the illustrated exemplary embodiment of the invention, comprises a body member, indicated generally as 10, having a generally circular upper portion 11 upon which the pressure rolls are mounted, as will presently more fully appear, and provided with a central opening 12 for passage of the barrel being turned, and having a generally rectangular lower portion 13 provided with screw holes 14 for securing the body member by means of screws 15 to the side of the lathe carriage 16 toward the tail stock 17. The rearward side of the body member is provided with a peripheral reinforcing flange 18 and radially arranged reinforcing webs 19.

Upon the outer side of the body member there is provided a pedestal bracket 20 having a recess 21 in its upper face in which is secured a double-acting air cylinder 22 provided with a piston 23 extending downwardly from the cylinder 22 into a cylindrical opening 24 in the bracket. A vertically reciprocating rod 25 is connected at its upper end to the lower end of the piston by a coupling 26 and is guided at its lower end by a cylindrical plunger extension 27 engaged in the vertical passage 28 of a bearing portion 29 provided upon the outer side of the body member in vertical line with the air cylinder. An adjustable screw plug 30 having a central air hole 31 is provided in the lower end of the passage 28 to limit the downward movement of the rod 25. The rod 25 is provided with a vertical slot 32 having a cross pin 33 extending across it, this pin being pivotally mounted in the rod and having opposed flats 34—34 engaged by the slotted end 35 of the operating arm 36 of the pressure roll operating cam plate or spider 37.

The cam plate 37 is rotatably mounted upon the forward face of the body member, being provided with a cylindrical bearing opening 38 engaged by a bearing bushing 39, secured in the opening 12 of the body member by a clamping nut 40, screwed upon its rearward threaded end portion 41 within an annular recess 42 surrounding the opening 12. The bushing projects forwardly from the body member, being provided

with an annular shoulder 43 engaging the face of the body member and with a flange 44 engaging the face of the cam plate, the distance between the bushing 43 and the flange 44 being slightly greater than the thickness of the cam plate 37, so that the cam plate can rotate freely on the bushing.

The cam plate 37 is provided with three side edges defined by the three sides of an equilateral triangle, the operating arm 36 projecting from one corner and having its slotted end 35 in radial line with the turning axis of the plate.

Outwardly of the three sides of the cam plate there are pivotally mounted upon the face of the body member 10 three bell crank rocker arms 45 equally spaced from each other and from the turning axis of the lathe, each having a hub portion 46 rotatably engaged upon a collared stud 47 having its shank secured in a hole 48 of the body member by a nut 49, the hub being rotatably retained upon the stud by a bearing washer 50 and a retaining screw 51. Upon the outer end of each rocker arm there is provided a collared stud 52 having its shank secured in a hole 53 in the rocker arm by a clamping washer 54 and screw 55. A cam roller 56 is rotatably mounted on the stud 52 of each rocker arm and is engaged in a cam slot 57 provided along the adjacent side of the cam plate. This cam slot is defined at its inner side by the flat surface of the side of the cam plate and at its outer side and ends by a yoke member 58 secured upon the side of the cam plate by screws 59—59, the angle of the cam slot being such that as the cam plate is rotated in counter-clockwise direction from the position as shown in Fig. 1 the cam roller is moved outwardly and the inner end of the rocker arm is moved inwardly. As may be noted in the preceding paragraph and from an inspection of Fig. 1 of the drawing, one edge of each cam slot is defined by one of the side edges of the cam plate, those side edges each being one side of an equilateral triangle. A cam slot so formed engages the corresponding roller 56 at a relatively sharp angle and a substantial component of any radially inward force applied to the roller 56 will tend to produce a rotation of the cam plate in the clockwise direction. Upon the inner end of each rocker arm there is provided a collared stud 60 having its shank secured in a hole 61 in the rocker arm by a clamping screw 62. A pressure roll 63 is rotatably mounted upon the stud 60 by means of an interposed ball bearing unit consisting of a row of balls 64, an inner race 65 secured upon the stud by a clamping screw 66, an outer race 67 secured within the pressure roll against an internal shoulder 68 by means of a retaining ring 69, and sealing rings 70—70 arranged between the inner and outer races at each side of the balls. The ball unit is of a self-aligning type wherein sufficient clearance is provided to enable the outer ball race to have limited tilting movement with respect to the inner ball race, the maximum tilt being of the order of about 5°. This permits the pressure roll to have a relatively large area of surface contact with the barrel being turned, while at the same time allowing the pressure roll to follow the taper of the barrel as the turning progresses, and as indicated by the dot-and-dash lines in Fig. 5. The periphery of the pressure roll is of cylindrical form, which is permitted by virtue of the self-aligning bearing.

The pressure rolls and their associated parts are enclosed in a guard 71 secured to the forward face of the body member by screws 72 engaged 73 pressure rolls, and consequently if the rolls are

through blocks 73 welded or otherwise suitably secured to the inner side of the peripheral wall of the guard. The peripheral wall of the guard is provided at its outer side with a slot opening 74 through which the operating arm 36 of the cam plate 37 extends, and the front wall is provided with a circular opening 75 concentric to the turning center of the lathe, a circular insert plate 76 having a central circular opening 77 being secured therein by screws 78 engaged in inwardly projecting lugs 79 secured to the guard. The lower side of the guard is open to allow coolant fluid and chips that may enter it to flow therefrom. At its lower inwardly disposed corner there is provided a clearance recess 80, in which the cross feed 81 carrying the cutting tool 82 engages in the forwardly disposed position of the tool, as shown in Figs. 1 and 2, the cross feed being mounted in the usual manner upon dovetail guideways 83 provided upon the longitudinally movable carriage 16.

A suitable coolant fluid, as for instance a mixture of soluble oil and water, is directed to the tool by a tube 84 mounted upon a fixture 85 secured by a screw 86 upon the upper side of the body member 10, this fixture having a suitable passage therethrough in communication with the supply line 87 for the coolant. The outlet end of the tube 84 is so disposed that chips and shavings are effectually removed from the work as they are produced by the tool, so that the barrel will be free of chips and other foreign matter at its area adjacent the tool which is engaged by the pressure rolls. The sealed bearings of the pressure rolls are such that they are effectually protected against the entrance of the coolant fluid, chips, and other foreign matter.

The operation is as follows: The gun or rifle barrel 88 to be turned is mounted between the head stock spindle 89 and the tail stock spindle 90 carried by the tail stock 17, as shown in Fig. 3, the carriage 16 and the follow rest mounted thereon being in the starting position clear of the gun barrel, with the tail stock spindle 90 projected through the opening 77 of the guard and its mounting chuck disposed within the bushing 38. In this position the pressure rolls are in outwardly moved position, the piston 23 being raised as shown in Fig. 1. Air pressure is admitted to the cylinder 22 to force the piston 23 downwardly causing the cam plate 27 to be rotated in counter-clockwise direction and the pressure rolls to be swung inwardly into contact with the tail stock spindle 90 at three equally spaced points around its periphery, the diameter of the spindle being the same as the turned barrel diameter. As the carriage moves axially along the barrel, the rolls leave the tail stock spindle and bear on the turned portion of the barrel following the contour thereof as shown in the dot-dash lines in Fig. 3. Although it is obvious that such an arrangement will readily follow over a section of decreasing diameter, it may not have been made clear that the preferred and most accurate operation results from using the follow rest as shown in the drawing by moving it in the direction of increasing diameter. The wedging action of a section of increasing diameter will exert a powerful force, which, as a result of the relatively sharp angle of the cams, may overcome the force of the air piston 23 and reverse the rotation of the cam plate. In this way, backlash or play in the system is completely eliminated. The cam plate imparts exactly the same motion to each of the

pressure rolls, and consequently if the rolls are

lined up so that their inscribed circle is in line with the lathe spindle and tail stock, this alignment is maintained regardless of the diameter of the inscribed circle. With no tool pressure tending to throw the barrel off center, it is evident that the pressure of the rolls on the barrel is equal for all three rolls. The action of the cutting tool on the barrel as it is turned normally tends to throw the barrel off center. As this occurs, however, the roll pressures redistribute themselves, exerting a resultant pressure on the barrel which counter-balances the tool pressure and thus maintains the concentricity of the turned portion of the barrel.

The form of the invention illustrated in the drawings and described herein is typical and illustrative only, and it is evident that the invention is capable of embodiments in other forms, all falling within the scope of the appended claims, which are to be broadly construed.

What is claimed is:

1. In a follow rest for machines for turning, grinding, or the like, a body member adapted for attachment to the tool-carrying carriage of the machine having an opening arranged for passage of the work, a plurality of equally spaced circumferentially arranged work engaging pressure rolls movably mounted on said body member having their turning centers coincident to an inscribed circle concentric to the turning center of the machine, a self-aligning bearing supporting each of said rolls for limited tilting movement, roll actuating means for simultaneously and equally imparting work engaging or disengaging movement to said rolls, and pressure means for urging said roll actuating means in work engaging direction.

2. In a follow rest for machines for turning, grinding, or the like, a body member adapted for attachment to the tool-carrying carriage of the machine having an opening arranged for passage of the work, a plurality of equally spaced circumferentially arranged work engaging pressure rolls movably mounted on said body member having their turning centers coincident to an inscribed circle concentric to the turning center of the machine, a self-aligning bearing supporting each of said rolls for limited tilting movement, each of said rolls having a substantially cylindrical peripheral surface, roll actuating means for simultaneously and equally imparting work engaging or disengaging movement to said rolls, and pressure means for urging said roll actuating means in work engaging direction.

3. In a follow rest for machines for turning, grinding, or the like, a body member adapted for attachment to the tool-carrying carriage of the machine having an opening arranged for passage of the work, a plurality of equally spaced circumferentially arranged work engaging pressure rolls movably mounted on said body member having their turning centers coincident to an inscribed circle concentric to the turning center of the machine, a cam member mounted on said body member for rotary movement about the turning center of the lathe for simultaneously and equally imparting work engaging or disengaging movement to said rolls, the engagement of said cam member with said rolls being such as to cause reverse movement of said cam by pressure exerted on said rolls, and yieldable pressure means for urging said cam member in work engaging direction.

4. In a follow rest for machines for turning,

grinding, or the like, a body member adapted for attachment to the tool-carrying carriage of the machine having an opening arranged for passage of the work, a plurality of equally spaced circumferentially arranged roll-supporting bell-crank levers pivotally mounted on said body member and having inner and outer ends, work engaging pressure rolls respectively carried upon the inner ends of said levers having their turning centers coincident to an inscribed circle concentric to the turning center of the machine, cam-engaging means respectively carried upon the outer ends of said levers, cam means engaged with said cam-engaging means for simultaneously and equally imparting work engaging or disengaging movement to said levers, and pressure means for urging said cam means in work engaging direction.

5. In a follow rest for machines for turning, grinding, or the like, a body member adapted for attachment to the tool-carrying carriage of the machine having an opening arranged for passage of the work, a plurality of equally spaced circumferentially arranged roll-supporting bell-crank levers pivotally mounted on said body member and having inner and outer ends, work-engaging pressure rolls respectively carried upon the inner ends of said levers having their turning centers coincident to an inscribed circle concentric to the turning center of the machine, cam rollers respectively carried upon the outer ends of said levers, cam means having a plurality of cam slots respectively engaged by said cam rollers for simultaneously and equally imparting work-engaging or disengaging movement to said levers, and pressure means for urging said cam means in work engaging direction.

6. In a follow rest for machines for turning, grinding, or the like, a body member adapted for attachment to the tool-carrying carriage of the machine having an opening arranged for passage of the work, a plurality of equally spaced circumferentially arranged roll-supporting bell-crank levers pivotally mounted on said body member and having inner and outer ends, work engaging pressure rolls respectively carried upon the inner ends of said levers having their turning centers coincident to an inscribed circle concentric to the turning center of the machine, cam-engaging means respectively carried upon the outer ends of said levers, cam means mounted on said body member for rotary movement about the turning center of the machine for simultaneously and equally imparting work engaging or disengaging movement to said levers, a radially extending arm carried by said cam means, and fluid pressure means including a piston operatively connected to said arm for urging said cam means in work engaging or disengaging direction.
